AUTOMATIC SUPPORT FOR FLATIRONS

Nathaniel B. Wales, New York, N. Y., assignor to
Industrial Patent Corporation, New York, N. Y.

Application April 21, 1948, Serial No. 22,359

6 Claims. (Cl. 38—79)

1

This invention relates to an automatic safety iron.

One of the objects of this invention is to achieve a "forget-safe" iron so that if the operator fails to up-end the iron after use, or to turn off the electric current, or place the iron on a holder, no fire damage will ensue. The only action necessary for perfect safety is the release of the handle of the iron by the operator.

A further object is to provide a "cold-lock" on an iron, or means to automatically maintain the retraction of the elevating element in the iron during a period of non-use so that it may be compactly stored, but only after it has cooled to a safe temperature.

Another object is to provide automatic means so that when the operator connects the iron to an electric outlet, the elevating element being in a retracted position, the iron will automatically elevate itself from the ironing board, or the like before its sole-plate has reached a scorching temperature.

A further object is to provide a predetermined timed interval after the operator releases the handle of the iron before it elevates itself so that if the operator desires to use both hands to shift the position of the piece being ironed the iron will remain in its normal position for a period of approximately six seconds before it elevates itself to its "temperature-safe" position even though the operator has released the handle.

Another object is to use a pedestal type of support element which in projecting from or through the sole-plate of the iron minimizes the reduction of the area of effective ironing of the sole-plate as compared to a flat foot type of support.

Further objects and pertinent details will be more specifically described and illustrated in the accompanying specifications and drawings in which similar numerals refer to similar parts:

Figure 1 is a side elevation partly in section, taken on line 1—1 in Figure 3, showing the supporting element in its extended position to elevate the iron from the operative surface.

Figure 2 is a view similar to Figure 1 showing the supporting element retracted and the iron in its normal operative position.

Figure 3 is an end elevation in section, taken on line 3—3 in Figure 2, to show the fulcrumed bifurcated actuating member which biases the supporting member of the iron on its under side by means of a rolling contact against a resilient pivotal element some parts being omitted.

Figure 4 is an enlarged sectional elevation of a dash-pot type of delayed action mechanism.

2

In Figure 1, numeral 1 is the sole-plate of the electric iron. The electric resistance heating element is not shown. Numeral 2 is the body of the iron, 3 is the handle suitably secured thereto. An L-shaped supporting member or pedestal 4, having a foot piece 5, is retracted into orifice 6 in the sole-plate 1, see Figure 2, and is maintained in one of two predetermined positions of full extension or complete retraction by the following components: A boss 7 secured to the upper side of element 4 centers the lower end of spring 8 which is secured at its upper end by boss 9 to the supporting bar 10 fixed to handle 3. Contacting the underside of supporting element 4 is roller 11 which acts through its contact with the underside of member 4 as a displaceable fulcrum thereto. Roller 11 is journaled in the bifurcated arms 12 of actuating member 13, which is pivoted by pin 14 to handle 3. The length of the bifurcated arms 12 of actuating member 13 is so proportioned from its pivoted point 14 to the contacting surface of roller 11, which bears on the underside of supporting member 4, that spring 8 is under compression. When the contacting point of roller 11 on the underside of element 4 is positioned as is seen in Figure 1 a distance or leverage X to the center line or axis of spring 8 under compression is formed and a downward compressive force is generated on element 4. This compressive force moves element 4 into its extended or support position and maintains it there, see Figure 1. The extended position of pedestal 4 is limited by the contacting of the extreme end 4a of pedestal 4 with the inner surface of body 2.

The manually actuated end 15 of actuating member 13 pivoted on pin 14 in recess 16 in handle 3 is engaged by spring 17 the upper end of which is recessed in handle 3 so that the force of spring 17 normally depresses the actuating member 13 to the position as is seen in Figure 1. However, when the handle 3 is manually grasped the fingers of the hand displace element 15 into an approximate position as is seen in Figure 2, wherein the bifurcated arms 12 of member 13 in which the fulcrum roller 11 is journaled have been moved clockwise about pivot 14 and consequently roller 11 has moved to the left along the bottom of support element 4, thereby eliminating torque arm X and creating torque arm Y as the roller 11 passed over and by the axis Z of spring 8. The support element 4 under the domination of torque Y recedes into the body 2 and foot 5 is forcibly restrained in its receded position as shown. The receding movement being limited by element 4 contacting the body 2 of the iron.

It is to be noted that support element 4 is restrained in its freedom of position within the limits of the deflection of spring 8 during its compression and expansion by boss 7 which enters within spring 8 and is substantially fixed thereto by the constant upward pressure exerted by roller 11 in either of its two terminal contacting positions with the bottom of element 4. However, to limit the freedom of support arm 4 within a tolerance so that the foot 5 may always enter recess 6 in sole-plate 1, as well as the relationship of orifice 19 with bi-metallic element 18, which will be described in detail below a fixed rod 20 suitably secured to the body 2 of the iron traverses slot 21 in the extreme end 4a of support member 4 to limit the freedom of support member 4 to an oscillating or rocking action about the axis of the spring 8.

To those skilled in the art it is evident that due to the coordination of spring 8, actuating member 13 and the biasing contact of the displaceable fulcrum roller 11 on element 4, together with spring 17 a snap-toggle movement is created using the axis of spring 8 as the neutral point. The counter force of spring 17 being so proportioned in respect to the force of spring 8 working through arm Y as seen in Figure 2 that a very slight contact of the normal gripping position of the hand on the handle 3 and member 15 is sufficient to maintain pedestal 4 in its reeded position.

A thermostatic element 18, which may be a conventional bi-metallic bar is secured to the iron to reflect the temperature of sole-plate 1 and is so proportioned that when it is deflected to a predetermined degree by its temperature it will freely enter orifice 19 in support element 4 as is seen in Figure 1, but when its temperature is lowered to a predetermined degree, likewise reflecting the temperature of sole-plate 1 it forms a stop against the normal extension of element 4 as is seen in full lines in Figure 2 in contrast to its dotted line position which it assumes when sole-plate 1 is at normal operating temperature. In this manner after the use of the iron when the operator by grasping handle 3 displaces member 15 and thereby raises support 4 into its retracted position, see Figure 2, if the heat responsive element 18 by its relative cooling normally assumes a position as is seen in full lines in Figure 2 the operator knows that the iron has cooled to a safe temperature to be stored, as the element 18 has latched the support in its retracted position. Conversely on making preparations to iron, the iron may be deposited on the ironing surface and plugged into the electric outlet and as the sole-plate 1 rises in temperature the element 18 is so calibrated as to move into that position by its increasing temperature to cause it to unlatch and the iron elevates itself before the sole-plate 1 reaches scorching temperature.

Referring to Figure 4 instead of spring 17 causing an immediate extension of the support member 4 on the release of the hand from handle 3 and member 15 a delayed extension of support member 4 may be desirable, so that the operator may be able to shift the piece being ironed without the iron automatically and immediately elevating itself. A dash pot giving a predetermined delay factor may be substituted for spring 17. To accomplish this, using a dash pot, a cylinder 22 secured into a recess in handle 3 is serviced by piston 23 and piston rod 24 which passes through a cross head 25 in cylinder head 26. Piston rod 24 is secured to actuating member 15

by a ball and socket 27 made with tolerances sufficient to accommodate the angular relationship of members 3 and 15. A spring 28 is interposed between handle 3 and manual actuating member 15. An inlet valve 29 in cylinder head 26 permits air to enter into cylinder 22 below piston 23 when actuating member 15 is upwardly displaced. Port 30 permits the upper end of piston 23 to be vented to the atmosphere. When manual actuating member 15 is released the air trapped in cylinder 22 delays the normal return of member 15 under bias of spring 28 to its position as shown in Figure 1. The tolerance between piston rod 24 and cross head bearing 25 may serve to permit sufficient air leakage therebetween to occur to return actuating member 15 over a period of the desired number of seconds.

What I desire to protect by United States Letters Patent is encompassed in the following claims.

I claim:

1. An electric iron comprising a sole plate having an orifice therein, a body secured to said sole plate, a handle secured to said body, a support member journaled at one end thereof upon said body and having its other end in register with said orifice for projection therethrough to its supporting position, a movable fulcrum suspended upon the body structure and slidably engaging the support member on its undersurface intermediate its ends, a spring element under compression connected to and interposed between a fixed part of the body structure and the upper surface of the support member to bias said support member against the fulcrum, said fulcrum adapted for movement to position the same to either one side or the other side of the normal engaging point between said spring element and the support member, and manual means for shifting the fulcrum from one of its positions to the other, whereby in one position of the fulcrum the support member under certain conditions may be moved to project its supporting end through said orifice to lift the iron to its support position and also whereby the support member is retracted within the body structure when the fulcrum is moved to its other position relative to said normal engaging point between the spring element and said support member.

2. In an electric iron according to claim 1 and including means to bias said manually shifted fulcrum into its iron support position.

3. In an electric iron according to claim 1 including a thermostatic latch thermally-responsive to said sole plate, and wherein said latch assumes a position to engage the support member to retain said member in its manually retracted position when said sole plate is at a relatively low temperature.

4. In an electric iron according to claim 1, including a thermostatic latch thermally-responsive to said sole plate, and wherein during approximate ironing temperature of the sole plate said latch will assume a position free from engagement with the support member to permit proper movement of said member for the purposes intended.

5. An electric iron comprising a sole plate having an orifice therein, a body secured to said sole plate, a handle secured to said body, a support member journaled at one end thereof upon said body and having its other end in register with said orifice for projection therethrough to its supporting position, a roller element pivotally suspended upon the body structure and

adapted to serve as a fulcrum for said support member, said roller engaging the support member intermediate its ends, a spring element under compression connected to and interposed between a fixed part of the body structure and the upper surface of the support member to bias said support member against the fulcrum-roller, said roller element adapted for swinging movement to position the fulcrum-roller to either one side or the other side of the normal engaging point between said spring element and the support member, and manual means for shifting the fulcrum-roller from one of its positions to the other, whereby in one position of the fulcrum-roller the support member under certain conditions may be moved to project its supporting end through said orifice to lift the iron to its support position and also whereby the support member is retracted within the body structure when the fulcrum-roller is moved to its other position relative to said normal engaging point between the spring element and said support member.

6. An electric iron comprising a sole plate having an orifice therein, a body secured to said sole plate, a handle secured to said body, a support member journalled at one end thereof upon said body and having its other end in register with said orifice for projection therethrough to its supporting position, a movable fulcrum suspended upon the body structure and slidably engaging the support member on its undersurface intermediate its ends, a spring element under compression connected to and interposed between a fixed part of the body structure and the upper surface of the support member to bias said support member against the fulcrum, said fulcrum adapted for movement to position the same to either one side or the other side of the normal engaging point between said spring element and

the support member, manual means for shifting the fulcrum from one of its positions to the other, whereby in one position of the fulcrum the support member under certain conditions may be moved to project its supporting end through said orifice to lift the iron to its support position and also whereby the support member is retracted within the body structure when the fulcrum is moved to its other position relative to said normal engaging point between the spring element and said support member, and a thermostatic latch thermally-responsive to the sole plate and serving as a means for controlling the operation of the support member according to predetermined temperature degrees of said sole plate, said latch being so mounted and proportioned as to assume a position to engage and form a stop for the support member to retain said member in its manually retracted position when said sole plate is at a relatively low temperature, and also whereby said latch during approximate ironing temperature of the sole plate will assume a position in register with an orifice in said support member to permit passage therethrough and thereby free movement of said member to its support position.
